LOAD HOOK CONNECTION

Charles S. Schroeder, Philadelphia, Pa., assignor
to The Yale & Towne Manufacturing Company,
Stamford, Conn., a corporation of Connecticut

Application August 25, 1944, Serial No. 551,127

2 Claims. (Cl. 59—86)

1

This invention relates to a chain hoist of the type disclosed in my Patents Nos. 2,335,571 and 2,342,091. In chain hoists of the class described, the chain utilized is of the sprocket actuated type in which the links are pivoted to one another about a series of parallel pivots. Therefore, the chain is flexible in one plane only.

I have found that chain of the particular type is susceptible to breakage when associated in a conventional manner with a clevis and hook block. Thus, it is common in the prior art to mount the hook block for pivotal movement relatively to the clevis and then mount the yokes of the clevis for pivotal movement relatively to a clevis support, with the clevis support being itself pivoted to the last of the chain links on an axis parallel to the parallel pivots of the chain links. Because the yokes of the clevis are pivotally mounted relatively to the clevis support about an axis very close to the axis on which the clevis support is pivoted to the last chain link, but at right angles thereto, it becomes possible to move the hook and hook block together with the yokes of the clevis in such a manner as to kink the links of the chain, placing them in an unnatural position. As a matter of fact, through this positioning of the chain links the effective length of the chain is also decreased.

It then sometimes occurs that when a heavy load is assumed by the chain through the hook and hook block, the chain will not bear up under the load because of its unnatural position. In addition, because the effective length of the chain is decreased, it will strike the hoist as it moves upwardly so as to damage the hoist. This is, of course, made possible because the limit mechanism does not function effectively with the chain in its unnatural position.

It is the object of my invention to provide means whereby it will be impossible to place the chain in the unnatural kinked position that has been found so objectionable by the industry. I have found that if the hook block is not allowed to pivot sharply with its clevis at right angles relatively to the lowermost chain link, as is possible in present structures where the clevis is pivoted on a clevis support itself pivoted to the chain, no kinking may occur. I, therefore, arrange for the mounting of the hook block for pivotal movement at right angles to the parallel pivots of the chain links as is required for manipulation of the hook, but about means that will prevent the pivotal movement that I have found to be the cause of the difficulties now encountered. As a further feature of my

2

invention, the mounting means for the hook block are preferably pivoted to the chain about a pivot shaft parallel to the pivots of the chain links.

As a detail feature of my invention, I utilize substantially the structure of the prior art with the clevis and clevis support arranged to form a functionally unitary member.

I have thus set forth the nature of my invention in order that those skilled in the art may better appreciate the relation of the invention to the prior art, and the contribution made thereby. While also I have indicated the operative theory of my invention, it should be understood that I may not be entirely correct in that theory and that my invention should not be limited thereby.

It is further emphasized that in reducing my invention to practice, I have preferred using mechanical means now employed in the art so as to reduce the cost of my invention, and that my invention should not be limited to the said means since other mechanisms for contributing the results of my invention will readily occur to those skilled in the art.

Referring now to the drawings,

Fig. 1 is a perspective view of a chain hoist of the type to which my invention is applied, the particular hoist being well illustrated and described in my patents supra.

Fig. 2 is an enlarged view of the means utilized for securing the hook block to the chain of the hoist with certain parts shown in section.

Fig. 3 illustrates just how the chain of the prior art may be kinked by the means now utilized for securing the hook block to the chain.

Fig. 4 is a section taken along lines 4—4 of Fig. 2.

Referring now more particularly to the drawings, the chain hoist in which my invention is incorporated is indicated generally by reference numeral 10 and utilizes a sprocket actuated roller load chain indicated generally by reference numeral 11. This roller chain comprises a series of links 12 pivoted to one another about parallel shafts 13 so as to be flexible in but one plane. It is, of course, understood that operation of a sprocket within the hoist 10 will move the chain 11 upwardly and downwardly.

In the prior art the lowermost link 12 of the chain 11 has pivoted thereto about a shaft 14, a clevis support 15. This clevis support 15 supports a clevis indicated generally by reference numeral 16, and having a pair of yokes 17. These yokes 17 are pivoted to the clevis support 15 about a horizontal axis substantially along the

line 18 illustrated in Figs. 1 and 3. The yokes 17 support at their lower ends a hook block 19, the hook block 19 rotating relatively to the yokes 17 on a horizontal axis parallel to the line 18. The hook block 19, of course, supports a hook 20 that is to be attached to the load.

It is possible for the relatively heavy hook 20 and hook block 19 to move the yokes 17 about the axis of the line 18, after which the movement of the clevis support 15 about shaft 14 will carry the clevis 16 downwardly so that the chain 11 will assume the kinked and unnatural position of Fig. 3. If a load is now applied to the hook 20, the chain because of its unnatural position, may be deformed or broken either upon assuming the load or after moving to an upper position as has already been indicated generally. Those skilled in the art will fully appreciate this condition and the incidental hazards resulting therefrom.

In Fig. 2 the hook block 19 is shown mounted on the yokes 17 about horizontal arms 21 extending from the hook block, so that the hook block may pivot relatively to the clevis as in all prior art structures, and as set forth supra. The yokes 17 are secured to the clevis support 15 so as to be incapable of movement relatively to the said clevis support. For the particular purpose, as best illustrated in Fig. 4, the extending arms 22 of the clevis support are formed square and they fit in square openings 23 in the upper ends of the yokes 17. It is, of course, possible to arrange in other ways for the securing of the yokes to the clevis support 15 in a manner which will not allow pivotal movement between the two. Thus, the ends of the yokes and the ends of the arms of the clevis support 15 of the structure of Fig. 3 may be deformed to yield the same results. As a further possibility, the clevis support 15 and clevis 16 may be formed as a unitary casting. In the claims of this application they are so considered and are termed a hook block support.

It will now be readily appreciated that the hook block 19 will still be rotatable as in Fig. 3 on a horizontal axis relatively to the clevis 16 and the yokes 17 thereof. However, a sharp pivotal movement of the clevis 16 relatively to the clevis support 15 is now not possible. It is now only possible to pivot the clevis 16 about shaft 14 relatively to the chain 11. Since clevis 16 is quite a bit longer than any chain link, the weight of the hook block 19 is always so disposed as to exert considerable force tending to maintain the hook block in the position of Fig. 2 and thereby to prevent the unnatural kinking of the chain. This is further true because hook block 19 is pivoted to the hook block support comprising parts 15, 16 on an axis at right angles to the axis on which the said hook block support is pivoted relatively to the links of the chain. Therefore, it becomes impossible to move the hook block and

chain into an unnatural position of the class indicated in Fig. 3.

A chain and hook block connection such as is illustrated in Figs. 2 and 4 has been tested repeatedly under all conditions and it has been absolutely impossible to manipulate the parts into a position of the type which has been found troublesome and dangerous. Those skilled in the art will now readily perceive that by a simple change of present structures, well known commercially, I have been able to obtain an extremely desirable and long sought result, and a result that has not been secured by others with mechanisms much more complicated and costly than that which I have herein shown and described.

I believe that the operation and construction of my invention will now be apparent to those skilled in the art.

I now claim:

- 20 1. In a combination of the class described, a sprocket roller load chain of the type having links that are pivoted to one another about parallel pivots so that said chain is substantially flexible in one plane only, a hook block, a clevis having a base and a pair of arms rigidly fixed thereto, said base being pivoted to the last of said links on a pivot axis parallel to said parallel pivots whereby said clevis is flexible relatively to said chain in only said one plane, and means pivotally mounting said hook block on the arms of said clevis on an axis at right angles to said parallel pivots.
- 25 2. In a combination of the class described, a sprocket roller load chain of the type having links that are pivoted to one another about parallel pivots so that said chain is substantially flexible in one plane only, a hook block, a clevis having a base and a pair of arms rigidly fixed thereto, said base being pivoted to the last of said links on a pivot axis parallel to said parallel pivots whereby said clevis is flexible relatively to said chain in only said one plane, and means pivotally mounting said hook block on the arms of said clevis on an axis at right angles to said parallel pivots.
- 30 3. In a combination of the class described, a sprocket roller load chain of the type having links that are pivoted to one another about parallel pivots so that said chain is substantially flexible in one plane only, a hook block, a clevis having a base and a pair of arms rigidly fixed thereto, said base being pivoted to the last of said links on a pivot axis parallel to said parallel pivots whereby said clevis is flexible relatively to said chain in only said one plane, and means pivotally mounting said hook block on the arms of said clevis on an axis at right angles to said parallel pivots.
- 35 4. In a combination of the class described, a sprocket roller load chain of the type having links that are pivoted to one another about parallel pivots so that said chain is substantially flexible in one plane only, a hook block, a clevis having a base and a pair of arms rigidly fixed thereto, said base being pivoted to the last of said links on a pivot axis parallel to said parallel pivots whereby said clevis is flexible relatively to said chain in only said one plane, and means pivotally mounting said hook block on the arms of said clevis on an axis at right angles to said parallel pivots.
- 40 5. In a combination of the class described, a sprocket roller load chain of the type having links that are pivoted to one another about parallel pivots so that said chain is substantially flexible in one plane only, a hook block, a clevis having a base and a pair of arms rigidly fixed thereto, said base being pivoted to the last of said links on a pivot axis parallel to said parallel pivots whereby said clevis is flexible relatively to said chain in only said one plane, and means pivotally mounting said hook block on the arms of said clevis on an axis at right angles to said parallel pivots, the distance on said clevis between its pivot to said chain and the pivot axis of said hook block, being at least as great as the length of two of said chain links.
